UNITED STATES PATENT OFFICE.

LEWIS M. ROBINSON, OF MATTEAWAN, NEW YORK.

AUTOMATIC MAIL-SLOT ALARM.

No. 919,081.

Specification of Letters Patent.

Patented April 20, 1909.

Application filed December 11, 1908. Serial No. 467,094.

To all whom it may concern:

Be it known that I, LEWIS M. ROBINSON, a citizen of the United States, residing at Matteawan, in the county of Dutchess and State 5 of New York, have invented new and useful Improvements in Automatic Mail - Slot Alarms, of which the following is a specification.

This invention is an improved automatic 10 mail slot alarm for use in buildings, on doors or mail receiving boxes or other like objects which have slots through which mail matter is passed, the object of my invention being to provide an improved alarm for use in connection with a mail slot so that when mail matter 15 is put through the slot by the postman, the said apparatus will close an electric circuit automatically and thereby sound an alarm.

20 The invention consists in the construction, combination and arrangement of devices hereinafter described and claimed.

In the accompanying drawings:—Figure 1 is an elevation of an automatic mail slot 25 alarm constructed in accordance with this invention. Fig. 2 is a sectional view of the same on the plane indicated by the line *a—a* of Fig. 1. Fig. 3 is a similar view on the plane indicated by the line *b—b* of Fig. 1. Fig. 4 is a detail perspective view of the 30 actuating arm. Fig. 5 is a similar view of the circuit closing operating arm.

A door, box or other device having a mail receiving slot A is indicated at B. Below the 35 slot A is a stop 1, the flap or cover which closes the mail slot on the inner side of the door is indicated at 2 and is pivotally connected at its upper corners, as at 3, to a plate 4 which may be readily secured to the door 40 or other object as by means of screws 5. The said plate is further provided with bearings 6 for a rock shaft 7. An arm 8 is secured to the said rock shaft as by means of a screw 9 and the free end of the said arm bears on 45 the cover or flap 2 so that, when the latter is opened by the passage of mail matter through the mail slot, said arm 8 will be turned angularly and the rock shaft will also be caused to partially turn. An arm 10 50 which is shorter than the arm 8 is also secured to the rock shaft as by means of a screw 11. A spring 12 is employed which tends to turn the rock shaft in one direction and to

keep the arm 8 in engagement with the flap or cover 2. The said arm 10 is provided on 55 its under side with a notch 13.

An insulating plate 14 is secured on the plate 4 as by means of screws 15 and serves as a brace for a binding post or wire connection 16 and also as a brace for a post 17 which has 60 a guide slot 18. A spring circuit-closing wire 19 is secured at one end at the base of the post 14, is electrically connected therewith and its free end operates in the guide slot 18 of the post 17 and also engages the 65 notch 13 in the arm 10. An adjusting screw 20 is attached to and properly insulated from the post 17 and forms a connection for a wire or wires which constitutes portions of the electric circuit including a suitable battery 70 and an electric bell (not shown) being indicated at 21 in Fig. 1. Normally, while the cover 2 is closed, the arm 10 serves to depress the free end of the circuit closing wire 19 so as to keep said wire out of contact with 75 the screw connector 20 hence opening the circuit. When mail matter is passed through the slot A it necessarily raises the cover or flap 2 and the latter, as herein before stated, causes the arms 8 and 10 to partially turn to 80 together with the rock shaft 7 against the tension of the spring 12 and this movement of the arm 10 permits the spring circuit closing wire 19 to come in contact with the screw connector 20, thus closing the circuit and 85 causing the bell to be sounded. The flap or cover 2 normally closes by gravity and the spring 12 keeps the arm 18 normally in engagement with said cover or flap and causes the arm 10 to keep the circuit closer 19 out 90 of contact with the connector screw 20.

It will be understood that the mail slot cover or flap together with all the other parts of my improved apparatus is secured to the plate 4 and hence the device may be readily 95 installed on a door or other object or as readily removed therefrom when desired.

What is claimed is:—

1. A mail slot alarm apparatus comprising a base plate having bearings, a mail slot 100 closing cover or flap hingedly connected to said base plate, a rock shaft in said bearing having a rock arm and also having a device engaging said cover or flap and operated by the latter to turn said rock shaft when said 105 flap is open, a spring to turn said rock shaft

in the reverse direction, and a circuit closing device including an element operated by said rock arm.

2. A mail slot or alarm comprising a base plate having bearings, a rock shaft journaled in said bearings, a spring to turn said shaft in one direction, a pair of arms of unequal length attached to said rock shaft, a mail slot cover or flap hingedly connected to said base plate engaged by the longer of said arms and normally maintained by said longer arm

in a closed position, and a circuit closing device including an element operated by the shorter arm and normally held by said shorter arm in circuit opening position.

In testimony whereof I affix my signature in presence of two witnesses.

LEWIS M. ROBINSON.
